UNITED STATES PATENT OFFICE.

HERBERT D. SHAMBERG, OF NEW YORK, N. Y.

DESIGN FOR AN ELECTRIC GENERATING UNIT.

54,868.

Specification for Design.

Patented Apr. 13, 1920.

Application filed August 2, 1919. Serial No. 315,025. Term of patent 7 years.

To all whom it may concern:

Be it known that I, HERBERT D. SHAMBERG, a citizen of the United States, residing at New York, in the county of New York and State of New York, have invented a new, original, and ornamental Design for an Electric Generating Unit, as shown in the accompanying drawing and described in the following specification.

The figure is a perspective view of an electric generating unit showing my new design.

I claim:

The ornamental design for an electric generating unit as shown.

HERBERT D. SHAMBERG.

Witnesses:

IRA W. HENRY,
W. H. RUDOLPH.
